Primary Examiner — Austin Murphy(74) *Attorney, Agent, or Firm* — Maginot, Moore & Beck LLP(57) **CLAIM**

The ornamental design for a planer, as shown and described.

DESCRIPTION

FIG. 1 is a perspective view of a planer showing my new design;

FIG. 2 is a right side elevational view showing the design for the planer of FIG. 1;

FIG. 3 is a left side elevational view showing the design for the planer of FIG. 1;

FIG. 4 is a top elevational view showing the design for the planer of FIG. 1;

FIG. 5 is a bottom elevational view showing the design for the planer of FIG. 1;

FIG. 6 is a front elevational view showing the design for the planer of FIG. 1; and,

FIG. 7 is a rear elevational view showing the design for the planer of FIG. 1.

The broken line showing of a portion of the planer in the drawings is included for illustrative purposes only and forms no part of the claimed design.
